UNITED STATES PATENT OFFICE.

HENRY M. REICHENBACH, OF DETROIT, MICHIGAN.

ATOMIZER FOR INTERNAL-COMBUSTION ENGINES.

1,250,657.

Specification of Letters Patent.

Patented Dec. 18, 1917.

Application filed June 8, 1916. Serial No. 101,604.

To all whom it may concern:

Be it known that I, HENRY M. REICHENBACH, a citizen of the United States, residing at Detroit, in the county of Wayne and State of Michigan, have invented certain new and useful Improvements in Atomizers for Internal-Combustion Engines; and I do hereby declare the following to be a full, clear, and exact description of the invention, such as will enable others skilled in the art to which it appertains to make and use the same.

My present invention relates to atomizers for internal combustion engines, and relates to that type of atomizer in which a primary air inlet into the intake conduit, is supplemented by a secondary air inlet, the opening of which is controlled by a valve responsive to engine suction.

The present invention relates to certain improvements in the features indicated, also to improvement in the feature by which a gyroscopic or helical swirl is given to the secondary air supply, and to means by which the secondary air supply is made to mingle completely with the fuel-laden primary air supply.

My invention also relates to the provision of a primary fuel supply inlet and to a secondary fuel supply inlet of a special type, this inlet being also provided with a special means of supplying air.

In the drawings:

Figure 1 is a section of my improved device.

Fig. 2 is a bottom view of the same.

Fig. 3 is a cross section through the conduit just back of the primary fuel inlet.

Fig. 4 is a vertical section of my improved valve.

Fig. 5 is a horizontal section; and

Fig. 6 is a top view of my improved secondary fuel inlet valve.

In the drawings, 1 represents the atomizer of my internal combustion engine supplied with flanges 2, which, by means of bolts 3, may be secured to said engine. In the intake conduit 1' of my atomizer there is provided a throttle valve 2' adjustable by means of a lever 3'. At the extreme left there is shown a primary air nozzle 4 seated in the end of an inner conduit 5, and ad-

justable therein by any suitable means, such as the screw thread 6.

By this adjustment the primary air charge may be brought into suitable atomizing relation with the charging fuel rising through the fuel discharge pipe 7, which is provided with slots 8 through which the fuel is discharged by means of hydrostatic pressure and engine suction, and the length of which slots may be controlled by the adjusting plug 9 shown in Fig. 1.

The fuel discharge pipes are supplied from a constant level device, which is of the usual type, through pipe or fuel conduit 11 entering into a chamber 12 formed at the lower part of my device, this chamber being closed by a plug 13. Leading from the chamber 12 is a pipe 14, through which fuel may also be discharged to a part to be al-luded to later.

The primary air conduit 15 is circular in section, and is surrounded by a secondary conduit 16 circular in section for the most part. This secondary conduit has an extension 17 on one side, however, and is provided with flanges 18. Upon these flanges 18, which are square in shape, I mount a frame 19 of the size of the exterior of the flanges, and clamp the two together by means of screws 20.

Between the frame and the flanges last named, I suspend a valve, made of flexible elastic material or flexibly hinged, 21. This valve, when the engine is quiet, rests upon the inner face of the frame, as shown in Fig. 3. Under engine suction, however, the valve is bent inward, as indicated by the dotted lines in Fig. 3; and may be bent inward until it contacts with the exterior of the inner circular conduit. The secondary air supply enters the opening thus formed under the valve, and is deflected around the primary conduit and carried forward by engine suction in a gyroscopic spiral. When it reaches the end of the secondary conduit, it encounters the converging walls 22 of said conduit, and is compressed and forced upon the inner or primary fuel-laden air supply, and the two are thoroughly mingled.

It will be noted that the arrangement is such that the secondary air supply, on entering, passes under the primary air conduit

- and forward toward the opening between the two, where it encounters the primary air supply; this latter being laden with fuel is heavier than the secondary air supply and 5 has a tendency to fall. This tendency brings it into intimate mixture with the secondary air supply compressed by the walls 22 and driven by the pull of the engine, so that the two are completely mingled and the spiral motion not materially affected. This motion, moreover, serves to sweep the walls of the conduit near the engine, comparatively clean of precipitated fuel.
- 15 On the engine side of the throttle I arrange an opening 23, here shown in the top of the conduit, and a round this opening but eccentric thereto I provide a circular walled seat 24. Mounted within this wall 24 I have 20 a valve 25 adapted to turn within said walled seat by means of the handle 26. The valve is held in its seat by any suitable means, such as the screw 27, shown in Fig. 6, taking into a proper slot. Vertically within 25 said valve is a channel 28, mounted eccentric to the axis of the valve, and so that when the valve is turned into one position said channel registers with the opening 23 in the top of the conduit.
- 30 I arrange a horizontal passage 29 within said valve communicating with the channel 28 aforesaid at one end, and at the other registering with an opening 30 in the wall or seat.
- 35 The arrangement of these parts and openings is such that when the channel 28 registers with the opening 23 the passage 29 registers with the opening 30 in the valve seat. Communicating with the opening 30 is the 40 pipe 14 before referred to.
- It will be seen that when the throttle is closed, if the valve be turned so as to bring the channel 28 and opening 23, and the passage 29 and opening 30, into registry, 45 engine suction will be effective to pull fuel through the pipe 14 into the conduit on the engine side of the throttle, together with a supply of air entering through the channel 23, for priming or starting purposes.
- 50 I provide a nozzle 31 fitting in the passage 29, said nozzle provided with a narrow discharge opening, across which air entering channel 28, passes at right angles to the direction of fuel discharge.
- 55 After starting, the throttle valve being open, the valve 25 is turned to shut off the supply of air and fuel through the opening 23.
- This atomizer may be, if desired, cast in 60 one piece, or it may be in separated parts and the primary and secondary conduits united by screw threads indicated at 31.
- It will thus be seen that I have provided a simple and efficient atomizer for use in connection with engines of the internal com-
- bustion type in which atomized air and fuel are intimately and efficiently mixed, and as part of which I provide a suitable and efficient priming device.
- Having thus described my invention, what I claim as new and desire to secure by Letters Patent, is:
1. In an atomizer for internal combustion engines, in combination, a horizontal primary air supply conduit, of cylindrical form, a secondary air supply conduit surrounding said first named conduit at a distance therefrom, said secondary air conduit extending beyond and having an opening 70 for the admission of a secondary supply of air, and a spring deflecting valve, closing said opening, said valve adapted to open inward toward and against the walls of the inner conduit, whereby the secondary current is given a direction tangential to the 75 body of air passing through the primary conduit, which tangential direction becomes, under the pull of the engine, helical whereby the secondary volume of air acquires a swirling motion.
2. In an atomizer for internal combustion engines, in combination, a horizontal primary air supply conduit, of cylindrical form, a secondary air supply conduit surrounding said first named conduit at a distance therefrom, said secondary air conduit 95 extending beyond and having an opening for the admission of a secondary supply of air, a spring deflecting valve, closing said opening, said valve adapted to open inward 100 toward and against the walls of the inner conduit, whereby the secondary current is given a direction tangential to the body of air passing through the primary conduit, which tangential direction becomes, under 105 the pull of the engine, helical whereby the secondary volume of air acquires a swirling motion, and converging walls at the end of the secondary conduit, whereby the secondary current of air is forced inward upon and into admixture with the primary current.
3. In an atomizer for internal combustion engines, in combination, a conduit, an opening in a wall of said conduit, a valve seat eccentric to said opening, a valve mounted on said conduit in said seat adapted to close 115 said opening, a channel in said valve leading to the air, and adapted to register with said opening when the valve is in open position, there being a second channel in said valve connected to said first channel and when the valve is open, connected to a fuel supply.
4. In an atomizer for internal combustion engines, in combination, a conduit, an opening in the wall of said conduit, a valve, consisting of a fixed and a vertical rotatable part mounted adjacent said opening, the 120 rotating part having a vertical channel adapted to register with the conduit wall 125
- 130

opening when the valve is turned in one position and to close said opening when the valve is turned into another position, said channel being open to the air at its outer end whereby air may be admitted to the conduit, said valve being provided with a horizontal channel, communicating at one end with said first channel, an opening in the fixed part, said second channel and opening adapted to register when the valve is turned ¹⁰ to the air open position, and means for supplying fuel to said fixed part opening whereby both air and fuel may pass into the conduit in the open position of the valve.

In testimony whereof, I affix my signature.
HENRY M. REICHENBACH.
